RECOIL DEVICE FOR MACHINE GUNS

Robert H. S. Hughes, Baltimore, Md., assignor
of one-half to Milton Roberts, Baltimore, Md.

Application June 18, 1937, Serial No. 149,020

4 Claims. (Cl. 89—14)

This invention relates to machine guns of the type having reciprocable barrels, and particularly to means for controlling the recoil of the barrel and the rate of firing of the gun. By means of my invention, the rate of firing of the gun may be varied while the gun is in action.

In carrying out the invention, I provide in front of the muzzle of the gun barrel a recoil controlling attachment which is supported independently of the barrel and preferably upon the jacket which surrounds the barrel and is connected to the gun casing. This attachment comprises a hollow body having a seal port in line with the bore of the barrel and also having forwardly and rearwardly directed ports out of line with the bore of the barrel, and also laterally directed baffle ports, for the discharge of the products of combustion. Valve mechanism is provided for closing all of the ports, or for opening the forwardly directed ports only, or for opening the rearwardly directed and baffle ports only. By these means, as hereinafter explained, the recoil force applied to the barrel may be increased or decreased, as desired. I also provide in the gun casing means for adjusting the tension of the spring which returns the barrel and breech bolt to their firing positions, and I provide means under the control of the operator for simultaneously adjusting the valve mechanism on the recoil device and the spring tensioning means so that the rate of firing may be varied while the gun is in action.

In the accompanying drawings:

Fig. 1 is a side elevation of a machine gun equipped with my improvements;

Fig. 2 is a rear end view of the same, parts being broken away;

Fig. 3 is a vertical longitudinal section through a portion of the casing showing the mechanism for adjusting the tension of the spring for operating the bolt and for simultaneously actuating the flexible shaft which operates the port controlling means;

Fig. 4 is a section on the line 4—4 of Fig. 3;

Fig. 5 is a section on the line 5—5 of Fig. 3;

Fig. 6 is a section on the line 6—6 of Fig. 2;

Fig. 7 is a central longitudinal section through the forward ends of the gun barrel and jacket and through the recoil controlling device;

Fig. 8 is an end view of the controlling device, looking from right to left in Fig. 7;

Fig. 9 is a section on the line 9—9 of Fig. 7; and

Fig. 10 is a section taken diametrically through the valve which controls the baffle ports and discharge ports.

Referring to the drawings:

1 indicates a machine gun as a whole, 2 indicates the breech casing, 3 indicates the barrel jacket and 4 indicates the movable gun barrel,

the bore of which is indicated at 5. A front mounting bracket 4' and a rear mounting bracket 5' are secured to the breech casing, these brackets being adapted for connecting the gun to a suitable support. Rear and forward sights, 6 and 7, respectively, are shown mounted on the jacket.

The breech casing 2 is provided with the usual projectile feeding mechanism indicated at 8. Operating handles 9 are attached to the rear end 10 of the casing 2, by means of supports 10, and a trigger mechanism 11 is arranged close to the handles.

My recoil device R is secured to the barrel jacket 3 and the forward end of the gun barrel 15 is movable longitudinally within the rear portion of said device. The bolt 15 of the machine gun is conventionally shown in Figs. 3 and 5. The bolt has a socket 16 to receive the forward end of a rod 17 and the forward portion of a spring 20 18 which is coiled about the rod. The rear end of the rod fits within a socket 19 in a block 20. This block extends laterally through elongated slots 22 and 23 in the side of the breech casing and of a housing 21 which is attached to said casing and bears against an adjustable wedge-shaped stop 29, the slots forming a guideway for the block.

As in machine guns generally, the bolt 15 is adapted to be moved rearwardly after firing by 30 the recoil of the barrel and the force of this rearward movement of the barrel is used to cause ejection of the empty cartridge, to extract a cartridge from the cartridge belt and deposit it into the breech, and, lastly it cocks the gun. 35 The spring 18 is compressed by the rearward movement of the bolt and as the spring expands and moves the bolt forward the bolt loads the cartridge, locks the breech and fires the gun.

In the present invention the tension of the 40 spring is adjustable by moving the stop 29 vertically. A vertically arranged shaft 24 extends through openings 25 and 26 in the housing 21 and a collar 27, pinned to the upper end of the shaft, supports its. The portion of the shaft 45 within the housing is threaded as indicated at 28 and this threaded portion extends through a threaded opening 30 in the stop. The block 20 has a beveled face 31 which engages the oppositely beveled face of the wedge-shaped stop 29. It will be evident that if the threaded shaft is turned to adjust the stop 29 upwardly the block 20 will be moved to increase the pressure on the spring 18, and if the threaded shaft is turned to adjust the stop 29 downwardly, the 50 pressure of the block 20 against the spring will be decreased.

A gear casing 32 is secured to the lower side of the breech casing, as shown in Figs. 3 and 4. The lower portion of the shaft 24 extends through 60

an opening 32' in the upper wall of the casing and on the lower end of the shaft is secured a bevel pinion 33 which meshes with a bevel gear 34 rotatably mounted on a stationary shaft 35 which is supported in the side walls of the housing 32. A pinion 36 which is secured to and rotates with gear 34 meshes with a large gear 37 secured to a shaft 38 which extends through and is journaled in the side walls of the casing 32.

As shown in Fig. 6, the lever arm 39 is pinned to the end of the shaft 38 at the rear of the casing 32. The lever arm is slotted as at 40 and latch member 41 extends therethrough and is pivoted as at 42. As shown in Figs. 2 and 4, a toothed segment 44 is suitably secured to the casing 32. The latch 41 is provided with a tooth 45 which is adapted to engage the segment 44. One end of a helical spring 46 is fitted within a socket 47 in the arm 39, and the other end of the spring bears against the latch 41 to normally hold its tooth in engagement with the toothed segment 44. A pointer 50 on the arm 39 indicates on an arcuate scale 49 the setting of the arm.

From the foregoing it will be evident that by moving the arm 39 motion is transmitted through the gear train 37, 36, 34 and 33, to the shaft 24 upon which is threaded the wedge 29. Rotation of the shaft 24 will move the wedge vertically to increase or decrease the pressure on the driving spring 18. By the same movements of the arm 39 a cable 109, attached to one end of the shaft 38, will be rotated. This cable, which is encased in a flexible non-rotative covering 110, operates the port controlling valves of my recoil device R so that any adjustment of the valves is accompanied by an adjustment of the spring tensioning device. The forward end of the cable is connected to a shaft 101 journaled in lugs 97 and 98 depending from the body of the recoil device, and this shaft carries gears 100 and 104 for operating the valves. The recoil device R, as shown in Figs. 7 to 10, comprises a hollow body 60 having a sleeve 61 which extends within the forward end of the jacket 3 and is secured to the jacket by a collar 63 which is threaded onto the sleeve as shown at 62 and also has a threaded connection 64 with the inner wall of the jacket. A set screw 65 engaging the jacket, collar and sleeve, prevents relative rotation of these parts. The recoil device is thus secured to and supported by the jacket which connects it to the breech casing. The forward end of the gun barrel is externally threaded, as indicated at 66, and an internally threaded collar 67 is threaded onto the barrel and secured against rotation thereon by a set screw 69. This collar has a smooth periphery and forms a bearing for the gun barrel within the sleeve of the recoil device. The forward end of the collar 67 is substantially flush with the forward end of the gun barrel and forms with the end of the barrel a shoulder 78 of substantial area against which the gas pressure is applied in the operation of the gun.

The body 60 has a cylindrical combustion chamber 70 therein, the rear part of the chamber being formed by the part 61^a of the sleeve 61 which extends forwardly from the gun barrel, this portion of the chamber wall having a series of baffle ports 79 extending therethrough, and an inwardly extending annular shoulder 61^b is formed at the forward end of said portion, and from this shoulder the inner side wall of the

chamber extends forwardly to the periphery of an annular shoulder 74 at the forward end of the chamber. The body has a tubular extension 71 at its forward end through which extends a seal port 72 which is in axial alinement with the bore of the barrel. From the forward part of the chamber discharge ports 73 extend rearwardly and outwardly through its wall, the outer ends of the discharge ports being forward of the baffle ports, so that when the ports are open and the gun is fired the discharge from the rearwardly directed ports will be intercepted by the discharge from the baffle ports, the arrangement of ports in this respect being similar to the arrangement of ports in my Patent No. 2,191,484, dated February 27, 1940.

In addition to the rearwardly directed ports and baffle ports I also provide intermediate the rearwardly directed ports, a circular series of forwardly directed ports 77, these commencing as grooves 77^a in the side wall of the chamber at the shoulder 70 and extending through the forward wall of the chamber adjacent the tubular extension 71, these forwardly extending ports being in line with the shoulder 78 on the gun barrel.

An annular valve 80 surrounds the body portion and is movable to open and close the rearwardly directed discharge ports and the baffle ports. As shown in Fig. 10, the valve has spaced openings 82 and correspondingly spaced openings 83 adapted to register with the baffle ports 79 and rearwardly directed ports 73, respectively, in one position of the valve, to open said ports, and in another position of the valve all of the ports will be closed.

On the forward end of the body is arranged a disk-like valve 81, with circularly spaced openings 86 adapted to register with the forwardly directed ports 77 in one position of the valve and to close said ports in another position of the valve.

The gear 100 on the shaft 101 has a tooth 102 adapted to engage a notch 94 in the edge of the valve 81 which controls the forwardly directed ports, and the periphery 103 of this gear is adapted to engage arcuate surfaces 95-96 at opposite sides of the notch to hold the valve in any position of adjustment. Similarly the gear 104 on shaft 101 has a tooth 107 adapted to engage a notch 91 at the periphery of the valve 80 and the periphery 108 of this gear is adapted to engage arcuate surfaces 92 and 93 at opposite sides of the notch 91 to hold the valve in any position of adjustment. Cooling fins 84 are provided on the valve 80 and such fins 88 are also provided on the valve 81, and fins 12 (Fig. 7) may be provided on the body of the recoil controlling device, to dissipate the heat from these ports when the gun is in action, so that the valves will fit closely and not be distorted by excessive heating of the ports.

In the positions shown in Figs. 7, 8 and 9 all valve controlled ports are closed, the control lever 39 is in the mid position as shown in Figs. 2 and 4 and the wedge 29 for adjusting the pressure on the spring 18 is also in mid position. In this position of the lever 39 the highest gas pressure prevails in the combustion chamber of the recoil device when the gun is fired, and hence the greatest gas pressure is applied to the shoulder 78 on the gun barrel and there is practically no recoil pressure applied to the barrel jacket, on which the recoil controlling device is mounted. In this mid position of the control lever the greatest rate of fire results because the gun bar-

rel is driven backwardly at high velocity and the pressure of the spring 18 is such as to ensure rapid return of the breach block and barrel.

Moving the control lever to the left in Fig. 2

- 5 (to the right as viewed in Fig. 4) adjusts the wedge 39 upwardly and increases the pressure on the spring 18 and turns the shaft 38, cable 109 and shaft 101 counter-clockwise as viewed in Fig. 8. With a sufficient movement the tooth 102 on the gear 100, engaging the notch 94 in the valve 87, will completely uncover the forwardly directed ports, while the rear valve 80 will remain closed; or by a shorter movement of the lever the forward ports can be only partly opened, 10 15 leaving the rear valve closed. Opening the forward ports lessens the gas pressure in the combustion chamber when the gun is fired, and hence the gun barrel will not be driven backward with the same velocity as when these ports are closed 20 and although the wedge 39 will be adjusted upwardly in opening the forward ports, increasing the tension of the spring 18, the stored energy in the spring will not compensate for the slowing down of the rearward movement of the barrel, 25 and the rate of fire will be decreased. The amount of decrease will depend upon the extent to which the forwardly directed ports are open.

Moving the control lever to the right in Fig. 2

- 30 (to the left as viewed in Fig. 4) adjusts the wedge 39 downwardly and decreases the pressure on the spring 18 and turns the shaft 38, cable 109 and shaft 101 clockwise, as viewed from the forward end of the control device, Fig. 8, or counterclockwise as viewed in the section, Fig. 9. In this movement the tooth 102 on the gear 100 moves out of engagement with the valve 87, leaving the forwardly directed ports closed and the tooth 107 on the gear 108 moves the valve 80 to open the rearwardly directed ports 73 and the baffle ports 79. If the movement of the control lever is sufficient to completely open the rearwardly directed ports and the baffle ports, the gas pressure in the combustion chamber when the gun is fired will be at a minimum and the pressure applied to the spring 18 by the wedge 29 40 will be at a minimum and the rate of fire will be slowed down both by the reduced rearward velocity of the gun barrel and decreased energy stored in the spring which returns the barrel. 45

- 50 In intermediate positions of the control lever the rearwardly directed ports and baffle ports may be only partly opened and the gas pressure, acting against the gun barrel when the gun is fired, will be greater or less according to the position of the valve 80 so that the velocity with which the barrel is driven backwardly will be varied accordingly, thus varying the rate of fire.

- 55 One important advantage of being able to change the rate of fire while the gun is in action, is that the gunner may change the rate so as to eliminate what is commonly called resonance. While at one speed there may be vibration, annoying the gunner, a slight adjustment of the rate of fire may substantially reduce this cause 60 of annoyance.

I claim:

1. The combination with a machine gun comprising a reciprocable barrel, a breech bolt and a spring adapted to be placed under tension by the recoil of the barrel and to return the bolt and barrel to firing positions, of a hollow recoil attachment supported independently of the barrel at its muzzle, said attachment having in its wall a seal port in line with the bore of the barrel and

having also forwardly directed ports and rearwardly directed ports, out of line with the bore of the barrel, for the discharge of the products of combustion to the atmosphere to affect the force of the recoil, port controlling means adjustable on the attachment for varying the effective areas of said forwardly and rearwardly directed ports, means for adjusting the tension of said spring, and manually controlled means for simultaneously moving said port controlling means and said spring tension adjusting means. 10

2. The combination with a machine gun comprising a reciprocable barrel, a breech bolt, a spring adapted to be placed under tension by the recoil of the barrel and to return the bolt and barrel to firing positions and means for adjusting the tension of said spring, of a hollow recoil attachment supported independently of the barrel at its muzzle, said attachment having in its wall a seal port in line with the bore of the barrel and having also forwardly directed ports and rearwardly directed ports, out of line with the bore of the barrel, for the discharge of the products of combustion to the atmosphere to affect the force of the recoil, a valve adapted to open and close the forwardly directed ports, a valve adapted to open and close the rearwardly directed ports, manually controlled means for moving said valves in succession to either their open or closed positions, as desired, and for simultaneously adjusting said spring tensioning means. 20

3. The combination with a machine gun comprising a reciprocable barrel, a breech bolt, a spring adapted to be placed under tension by the recoil of the barrel and to return the bolt and barrel to firing positions and means for adjusting the tension of said spring, of a hollow recoil attachment supported independently of the barrel and its muzzle, said attachment having in its wall a seal port in line with the bore of the barrel and having also forwardly directed ports and rearwardly directed ports, out of line with the bore of the barrel, and baffle ports at the rear of rearwardly directed ports, a valve adapted to open and close the forwardly directed ports, a valve adapted to open and close the rearwardly directed ports and baffle ports, manually controlled means for moving said valves in succession to either their open or closed positions, as desired, and for simultaneously adjusting said spring tensioning means. 40

4. The combination with a machine gun comprising a casing and a barrel jacket extending forwardly from the casing, of a hollow recoil controlling attachment having a sleeve fitting within 55 and secured to the forward end portion of the jacket, a reciprocable barrel within the jacket, said barrel having an external collar at its forward end in sliding engagement with the interior of said sleeve, said attachment having a seal port in line with the bore of the barrel and having also forwardly directed ports and rearwardly directed ports out of line with the bore of the barrel, for the discharge of the products of combustion to the atmosphere to affect the force of the recoil, rotatably mounted valves on the attachment for varying the effective areas of said forwardly and rearwardly directed ports, respectively, said valves having heat radiating fins at 60 their peripheries, and manually controlled means 65 for operating said valves from the rear end of the gun. 70

ROBERT H. S. HUGHES.
